ELECTRICAL ROOM-DEODORANT VAPORIZER
CASING

Carl B. Lien, 9229 W. Grand Ave., Franklin Park, Ill.

Filed June 1, 1960, Ser. No. 60,815

Term of patent 14 years

(Cl. D16—2)

Fig. 1 is a top plan view of an electrical room-deodorant vaporizer casing embodying my new design;

Fig. 2 is a bottom plan view;

Fig. 3 is a front elevational view;

Fig. 4 is a left side elevational view, the right side, not shown, being substantially the same;

Fig. 5 is a rear elevational view; and

Fig. 6 is a rear perspective view showing the right side thereof.

I claim:

The ornamental design for an electrical room-deodorant vaporizer casing, substantially as shown and described.
